O. KUPFERMAN
SOCKET FOR ELECTRIC LAMPS

Filed Dec. 2, 1922

UNITED STATES PATENT OFFICE.

OSCAR KUPFERMAN, OF BROOKLYN, NEW YORK.

SOCKET FOR ELECTRIC LAMPS.

Application filed December 2, 1922. Serial No. 604,486.

To all whom it may concern:

Be it known that OSCAR KUPFERMAN, a citizen of the United States, residing at Brooklyn, in the county of Kings and State of New York, has invented certain new and useful Improvements in Sockets for Electric Lamps, of which the following is a specification.

The present invention relates to electric 10 sockets particularly electric candle sockets, and has for its principal object to simplify the construction and manipulation of the switch mechanism, and to provide means for the attachment of the socket to the fixture in 15 such a way that it can be readily detached without twisting or breaking the wires or causing short circuits.

The sockets of the hitherto known construction are in many respects objectionable. 20 One of the main objections thereof resides in that they are threaded to the fixture so that when detaching the sockets from the latter, the wires become twisted or broken causing short circuits or the threads are stripped 25 rendering the socket useless.

Another objection is the use of a pull-chain or press button for the manipulation of a switch mechanism, because by pulling the chain or pressing the button roughly the 30 socket is shaken, owing to which frequently delicate parts of its switch mechanism or the sections of the insulation body thereof become loose, rendering the socket defective.

Another drawback of the old socket construction is the use of a return spring, usually a coil, in connection with the contact 35 ratchets, because such spring at slight shocks or jars becomes deranged and ceasing to operate renders the socket useless.

With my invention all the above named 40 objections are entirely avoided.

My invention will be fully understood by references to the accompanying drawing in which similar reference characters denote 45 corresponding parts and in which Fig. 1 is a longitudinal section of my novel socket shown as applied to a stationary fixture; Fig. 2 is a section on line 2—2 of Fig. 1; Fig. 3 is an enlarged section of the switch 50 mechanism and Fig. 4 is a cross section on line 4—4 of Fig. 3.

In the drawing 10 denotes a stationary fixture in the form of a hollow arm of usual construction, the free end 10' of which is 55 threaded. Heretofore the electric sockets have been screwed directly to this threaded

end, as a result of which the wires become twisted and often break when unscrewing the socket.

The socket constructed according to this 60 invention comprises the ordinary threaded metal shell 11 adapted to receive the bulb 12 and to have attached to it the insulation body 13 in which the switch mechanism 14 is mounted. The insulation body 13 is composed of two separate solid parts, an upper 65 plug or part 13' and a lower disc shaped part 13² which are arranged in superposed position and are separated to form a freely accessible space in which the switch mechanism 14 is accommodated. The two parts 13' and 13² of the insulation body are rigidly connected together by longitudinally extending and oppositely arranged bars 15, 16 of conductive material to serve at the same 70 time as binding posts for the electric wires 18. At their lower ends these binding posts are perforated to receive sleeves 17 of insulating material which constitute bearings for a threaded cross shaft 19 adapted to carry a 75 ratchet commutator 20. This shaft is extended at one end to project outwardly beyond the corresponding binding post and to have threaded thereon a serrated nut 21 or the like to serve as a handle for manipulating 80 the ratchet commutator. The commutator 20 is of the usual construction, that is, consists of a wheel shaped body of insulation material formed with four ratchet teeth the 85 outer faces of two of which are covered with 90 conducting material while the others are of the same non-conducting material as the body portion. The coverings 22 for the two teeth are constituted by lateral projections of a disc 23 of conducting material arranged 95 adjacent one face of the wheel 20. The commutator wheel 20 is formed with a square central hole 20' which fits on a square 19' formed on the shaft 19. It is fixed in its position on said square 19' by sleeve shaped 100 nuts 24, 25, threaded on the shaft 19. 26, 27 denote metal washers and 28 a washer of insulation material.

The circumferential surfaces of the teeth of the ratchet 20 are circularly curved eccentrically to the body portion of the wheel so that the circumferential face of each tooth constitutes a cam whose crest is at the projecting end of the tooth. The end face or drop of each tooth extends in radial 110 direction. Cooperating with these teeth of the commutator, are two members 29 and

30 of conductive material arranged at diametrically opposite sides of the wheel. Of these members, the member 29 is carried by and conductively connected to a screw bolt, 5 which extends longitudinally through the section 13' of the insulation body and whereby the shell or metal socket proper 11 is fixed to the latter. This member is formed of a spring plate, which from its 10 point of attachment extends downwardly in a vertical plane intersecting the wheel body on a line substantially tangent to the body portion thereof. At an intermediate point, the plate 29 is bent laterally in a direction 15 away from the wheel as at 29' and then again downwardly in a sloping manner toward the wheel as at 29''. At its lower part, the sloped portion 29'' is curved as at 29''' to conform with the curvature of the 20 cam surface of a tooth and is capable of tightly embracing a tooth of the wheel and owing to its spring force tends to hold the wheel steadily in position. This member 29 by virtue of its particular shape and in conjunction with the cam shaped ratchet teeth will perform three functions. In sliding over the sheathed and unsheathed faces of the teeth, it will act as a circuit make and break element. In cooperation with the 30 radial end faces of the ratchet teeth, it will act as pawl preventing retrograde movement of the wheel. Finally, owing to its tendency to maintain its normal position and to the particular shape of the cam, the member 29 will exert a spring force on the wheel, which will prevent the latter from stopping short of a complete turn of a tooth and whereby the function of the commutator or that of the make and break mechanism will be rendered positive and sparking avoided. The second member 30 is in form 40 of a recessed arm or plate, also of resilient and conductive material, fixed to the binding post 15 as at 30' and extending across the wheel body. The free end of this arm is formed with a lateral extension 30'' adapted to extend into the path of the ratchet teeth. This member 30 is adapted normally to extend in a vertical plane removed from the center of the wheel a distance substantially equal to the radius of the latter and with its extension to bear on the wheel body. By extending across the drop of a tooth, it will act as a barrier preventing 50 positively retrograde movement of the commutator.

The binding posts 15 and 16 are secured in position by the longitudinal bolts 33, 34 extending through the section 13' of the insulation body and of which the bolt 33 carries the contact tongue 35 which extends into the metal shell 11 to make contact with the central contact point 12' of the bulb 12 in the usual manner. The disc shaped part 14 of the insulation body has fixed to

its bottom a member 36 extending diametrically across the face of the disc 13'' and formed centrally with a cylindrical projection or boss 37. This boss serves as a part of the means for attachment of the 70 socket to the fixture in such a manner that the socket can be attached and detached without twisting or the danger of breaking the wires. To this end I employ a nipple 38 which comprises two vertical superposed disc or ring shaped members 38', 38'' arranged at a short elevation from one another and connected together by vertical ribs 39. The ring shaped members are centrally perforated, the lower one 38' having its central bore or perforation threaded so that it may be screwed onto the threaded end 10' of the fixture or arm 10. The central perforation of the upper ring 38'' is adapted to serve as a socket for the cylindrical boss 37 which is adapted to snugly fit therein and to be clamped in position by a set screw 40 or the like. A set screw 41 may also be used for the lower ring shaped perforation to insure its position on the fixture. The wires 18 conveyed through the fixture 10 are branched outwardly through the free space between the two rings 38', 38'' in opposite directions and are attached to the binding posts as at 15', 16'. The disc shaped part 13'' of the insulation body may be grooved as at 13''' to accommodate the wires. As usual, the insulation body and the switch mechanism are enclosed in a sheath 43 of insulation material around which is mounted the tube or cylinder 44 of porcelain or the like to represent a candle. The lower part of the tube 44 is longitudinally slotted as at 44' which slot extends to the lower end thereof and serves as a passage for the projecting end of the shaft 19 carrying the knob 21.

By the construction hereinbefore described an electric candle socket is produced which, as will be readily seen, is very simple in construction and manipulation and which owing to the fact that the switch mechanism is composed of only a few parts will be very durable and safe for use. Owing to the provision of the nipple between the socket and the fixture the attachment and detachment of the socket from the latter are rendered easy and convenient.

What I claim is:

1. In an electric socket, the combination with a fixture having a threaded nozzle, of a boss projecting from the bottom of said socket, a nipple having a threaded bore to screw on said nozzle and a plain bore to serve as socket for said boss and means for locking said boss in said socket.
2. In an electric socket, the combination with a fixture having a threaded nozzle, of a boss projecting from the bottom of said socket, a nipple having lateral recesses and

an internally threaded bore to thread on said nozzle and a plain bore forming a socket for said boss, and means for locking said boss in said socket, said recesses serving for the passage of electric wire.

3. In an electric socket, an insulation body divided into two superposed parts separated from one another to form a freely accessible space, a switch mechanism arranged in said space and including two opposite binding posts fixed to said parts and separating the latter, insulation bearings in said posts, a manually operable shaft borne in said bearings, a ratchet commutator on

said shaft, two vertical resilient members 15 adapted to cooperate with said commutator both as pawls and conductors, a projection on said insulation body, a mouth-piece adapted to be fixed to a fixture and to receive said projection, and means for clamp- 20 ing said projection in said mouthpiece.

In testimony whereof I affix my signature in presence of two witnesses.

OSCAR KUPFERMAN.

Witnesses:

MAX D. ORDMANN,
JOSEPH T. McMAHON.
